UNITED STATES PATENT OFFICE.

ALFRED LOUIS SOHM, OF LOS ANGELES, CALIFORNIA, ASSIGNOR TO THE SOHM ELECTRIC SIGNAL & RECORDING COMPANY, OF SPOKANE, WASHINGTON, A CORPORATION OF ARIZONA.

ELECTRIC RECORDING INSTRUMENT.

1,075,513.

Specification of Letters Patent.

Patented Oct. 14, 1913.

Application filed July 26, 1910. Serial No. 574,606.

To all whom it may concern:

Be it known that I, ALFRED L. SOHM, a resident of the city and county of Los Angeles, State of California, have invented 5 a new and useful Improvement in Electric Recording Instruments, of which the following is a specification.

My invention has reference to electric signal and recording systems; and it provides a 10 simple and efficient means whereby a cheap and inexpensive apparatus is capable of use with a large number of outlets, with a small number of circuiting wires.

The apparatus herein is designed to record 15 and indicate the year, month, day, hour and minute, and the a. m. or p. m., and also an "in" and an "out" designation, and any other special character, as, for instance, a watchman's report, or a "mis- 20 take" or rectifying notice, on a printed slip, which slip may be torn off at intervals and preserved.

It is also designed to designate the number of the employee, when used with an employee's entrance plate, or to designate the 25 room number, when used in hotels or public buildings, or the station if used in fire alarm or police systems, the object being to make an easily operated piece of mechanism 30 whereby a single circuit will contain in itself the capacity for any series of numbers which may be necessary for either of these purposes, as will now be set forth in detail.

In the drawings, Figure 1 is a side elevation of my improved electric signal and recording mechanism. Fig. 2 is a top or plan view of the same. Fig. 3 is a front view of a portion of the tripping and reversing device for the ink ribbon mechanism. Fig. 4 is a view of part of the vertical arm which carries the tripping device. Fig. 5 is an edge view of the tripping device. Fig. 6 is a view of the rear side of 45 the link of the tripping mechanism. Fig. 7 is a view of the tripping device showing manner of changing the double-acting pawl from one wheel to the other. Fig. 8 is a view of the right hand end of the recording 50 mechanism. Fig. 9 is a vertical longitudinal section on line 9 of Fig. 11, of a portion of the base of the laterally-movable carriage which carries the type bar mechanism. Fig. 10 is a vertical cross section of

the time printing magnets and armature, 55 showing special construction of the core and armature. Fig. 11 is a plan view of the base plate of the mechanism. Fig. 12 is a vertical longitudinal section of the base plate along line 11 of Fig. 11. Fig. 13 is a rear end view of the removable frame which contains the mechanism for printing the time, and the paper feed rollers, and carries the inking ribbon. Fig. 14 is a vertical longitudinal section of this frame on line 14 of Fig. 13. Fig. 15 is a horizontal section of part of the frame, on line 15 of Fig. 13, and Fig. 16 is a diagrammatic view of the circuits.

In constructing my invention I provide a 70 rectangularly-formed base plate 14 of suitable metal, which is mounted on four legs 15, and this plate is surmounted by a top plate 16, which extends partially over the base plate, having a cut-out portion, as indicated by the dotted lines 17, in Fig. 11, thus forming two side members 18, between which is mounted the mechanism for carrying the ribbon wheels and the time printing mechanism.

Beneath the base plate 14, and secured thereto, are the magneto coils 20 for operating the time printing mechanism herein-after described as the "time coils", which are held by a bracket 21 to the base plate. 85 At one end is a horizontally-disposed rocking armature 22, which is hinged at its ends to brackets 23, at 24, and an arm projects horizontally in a longitudinal direction, below the base plate, terminating in an eye, to which is hinged a vertical link bar 26, the upper end of this link being hinged to the arm 79 which operates the time printing mechanism. The arm 25 operates through a slotted opening 27 in the base plate 14, and a flat spring 28, secured to the base plate and bearing on the arm 25, restores the arm to its normal position after each operation. The magneto coils 20 are connected up in a circuit including the battery 20^a and a 100 clock 20^b, which is provided with contact mechanism adapted to close the circuit at regular intervals. A magneto coil 30, for actuating the "in" and "out" mechanism, is also secured to the under side of 105 the base plate by a downwardly-projecting bracket 31, the lower end of which carries a pivoted armature bar 32. This armature bar

passes horizontally beneath the magneto coil 30, terminating in a dog 33, adapted to engage the lower end of the vertically-disposed armature 34. The upper end of this 5 armature is hinged to the bracket arm 35, at 36, where it is bent at right angles to form a horizontal member 37, the end of which has an eye that is hinged to a vertical link 38, which extends up and is hinged to the arm 78 that actuates the "in" and "out" segment of the recorder. The other 10 end of the armature lever 32, as at 39, serves as an armature which is actuated by a vertically-disposed magneto coil 40, the office of this coil being to disengage the dog 33 from the armature 34 when the printing operation takes place.

Mounted on the bed plate 14 is a laterally-movable plate 43, slightly smaller than the 20 base plate 14. This plate is designed to carry the type bar mechanism, and has a slight lateral movement. To provide for this movement the base plate 14, and also the base plate 43 of the carriage, are provided with four short laterally-extending and coinciding runway guides 44, adapted to receive the anti-friction balls 45. The lateral motion of this carriage is controlled by two pairs of electromagnets 46, 47, secured 25 transversely to the under side of the base plate 14, by means of brackets 48, the pole pieces of these magnets projecting toward each other, and between which is placed a vertical armature bar 49 which 30 projects down through an aperture 50 in the base plate 14, and has its upper end secured to the carriage 43 by means of 35 bolts 51.

One end of the armature 49 has a horizontal 40 projection 52 which lies between the two spring fingers 53, these fingers being secured to the base plate, at 54, so that normally the armature is midway between the pole pieces of the coils 46, 47, and if either 45 coil, on being energized, draws the armature laterally in either direction, and is then deenergized, the springs 53 will again restore the armature to its neutral position.

The carriage 43 has thereon two sets of 50 type bars and operating coils, preferably six at each end, the coils 56 of which are vertically-disposed and arranged in circular formation, the radii of their respective type bars 57 being from a common center, which 55 is alongside, or at one end of the time printing mechanism, so that when the printing of the numerals is performed by these type bars it will appear on the recorder tape along one margin and on a line with the 60 date of the operation. Each coil 56 has an armature 58, the outer end of which is hinged to a vertical post 59, the inner end being in contact with the segmental stops or notches 60 of the printing bar 57, and 65 so arranged that when the coil 56 is ener-

gized the drawing down of the armature 58 will cause the type bar to swing upwardly and print the character thereon, on the paper web.

The frame which carries the time printing wheels, the inking ribbon, the paper feeding rolls, the "in" and "out" segment and the pad against which the type bars operate, is adapted to slide in between the side members 18. This frame is made up 70 of the two side members 65 secured together at one end by a cross rod 66 and having across its rear end a vertical plate 67, on the upper end of which is mounted two ribbon wheels 68, each being secured on a threaded bearing stem 69 by a thumb nut 70 and a spider 71 to secure adjustment by frictional contact. Below these wheels, and on a line therewith, are rollers 72, each of which is located beyond the side plate 65, mounted 75 on an extension arm 73, integral with the plate 67. The inking ribbon 74 therefore passes through below these rollers from side to side, the ends being secured to the respective ribbon wheels 68.

The wheels for printing the year, month, day, hour, and other periods of time, are located on a fixed shaft 76 at the lower side of the rear end of the frame members 65. This shaft has also at one end a rocking 90 member 77, provided with an arm 78, which is hinged to the vertically-disposed operating link 38 heretofore described. On this rocking member or segment is the type character "In" and "Out."

The shaft 76 rests at one end in a yoke 80, which has an opening 81 through which the type bars 57 operate, and directly above, and on a line with the time printing wheels, is a horizontal pad 83, secured at its ends to 105 links 84, the upper ends of said links being hinged to the rear ends of a pair of oscillating levers 85. These levers lie alongside the frame members 65 and extend forward past the end of the said frame members terminating in a cross bar 86 which serves as an armature. The levers are hinged to the cross connecting rod 66 of the frame, so that the rear ends of these levers have a limited vertical movement which carries the 110 pad 83 up and down during the printing operation.

The paper feed rollers are mounted forward of and above the printing wheels, the upper roller 85' having at one or at both 115 ends a toothed wheel 86' which coacts with a dog 87 on the lower end of a hinged finger 88, the upper end of the latter being hinged to the lever 85, and, for purposes of convenience, a cross rod 89 serves the purpose 120 of uniting the ends of the levers 85 and also acts as a pivot pin for the finger 88 as well as for the link 84. Below the roller 85' is a smaller friction roller 90 mounted within the slotted guide ways 91 of the side mem- 125 130

bers 65, a spring 92 being employed at each end, within the guide way, 91, to keep the roller 90 in contact with the upper roller 85', and thus give a positive feed to the paper 5 94, Fig. 1, and also by dotted line 94, Fig. 14, which is fed through between these rollers, and issues from the frame so that it may be torn off along the edge of the frame plate 67.

10 The paper is fed from the paper supply roll 94', Fig. 1, mounted in a suitable place on the frame. I do not show a roll from which the paper is fed, as that feature involves nothing new in the art. The electro-15 magnets 96 for actuating this feeding mechanism are mounted on a frame at the front end of the top plate 16, this frame comprising the vertical end members 97, having a top cross connecting plate 98, this latter 20 plate being above the armature bar 86. The core 99 of each magnet 96 is concaved at its lower end, as at 100, Fig. 10, and the armature bar has conical points 101 adapted to enter the concaved ends of the cores when 25 the armature is drawn upwardly. The object of this construction is to bring the armature closer to the magnetic field of the cores, and at the same time give a greater range of movement to the armature. The cores of 30 the magnets are secured in sockets in the frame 98, and are readily removable.

The ribbon wheels 68 are actuated by a peculiarly formed mechanism so arranged that when the ribbon 74 is completely un-35 wound from one wheel 68, the tension of the feeding mechanism will automatically trip the feeding pawl and throw the latter into engagement with the other wheel of the ribbon, thus reversing the direction of movement of the ribbon without requiring any attention on the part of the user. This tripping and reversing mechanism is shown in detail in Figs. 3, 4, 5, 6, and 7. The printing pad 83 has attached thereto on its upper side 45 a cross vertical plate 105, having midway between its ends a vertical stem 106, which has its upper end slotted, as at 107, and held in vertical alinement by means of a horizontal post 108, secured to the upper end of the plate 67, and an adjustable screw 109 which passes through the slot 107, so that the stem 106 is free to move vertically.

On the front side of the cross plate 105, midway between its ends is hinged the lower 55 end of a link 111, at 112, the upper end of the link having a triangularly-shaped tripping pawl 113, hinged thereto by the pivot 114. The upper diverging ends of the tripping pawl have teeth 115 which are designed 60 to contact with the teeth 116 of the disks 117 which form a part of the ribbon rollers 68. As the toothed disks are on the same plane with the triangular-shaped pawl 113 between them, it is obvious that the link 65 111, in swinging laterally, will bring the

teeth 115 into engagement with one of the toothed-disks 117.

The stem 106 has stop-pins 118 alongside of the link 111 to limit its lateral movement, and on the rear side of the stem is a tubular housing 119, within which is a pin 120, seated against a spring 121, the pin passing through the stem 106 and having its rounded or pointed end resting against the rear side of the link and adapted to enter one of the 75 detents or countersunk holes 122 formed in the rear side of the link, as shown in Fig. 6. The action of the spring 121 is sufficient to hold, normally, the pin 120 in one of the detents 122, and thus prevent the link from 80 swinging over, but if there should be an extraordinary stress exerted laterally on the link the spring would permit the pin to disengage and thus allow the link to swing over and engage the pin with the other de- 85 tent.

As the triangularly-shaped tripping pawl 113 has a limb 123 extending below the pivot point 114, a coiled spring 124 connects the extension 123 with the pivot pin 112. The 90 object of this spring is to hold the triangularly-shaped tripping pawl 113 and the link 111 normally in line with each other. When, for instance, the stem 106 and pawl 113 are moved upwardly, as shown by dart 126, Fig. 95 3, the disk of the ribbon wheel is moved upwardly carrying the inking ribbon toward and around that wheel, as the friction spider 71 of the other wheel is not sufficiently strong to trip the pawl. If, however, the 100 ribbon should be entirely unwound from the wheel on the left side, and the pawl in moving upwardly should not be able to turn the toothed wheel in the right side, with which it is in engagement, the friction-pin 120 105 would become disengaged from the detent 122 and thus cause the upper end of the link 111 to swing to the left as shown in Fig. 7, and when the stem 106, and pawl 113, again move downwardly, the spring 124 110 would throw the upper end of the triangularly-shaped pawl to the left, thus causing it to engage with the teeth of the disk on the other ribbon wheel, with the result that the wheel on the left side would then begin 115 to take on the ribbon.

The operation of the mechanism is as follows: As shown by the diagrammatic view, Fig. 16, I employ three vertical columns of digits, from 1 to 0 inclusive, in order to signal or record any number up to and including 999. The carriage 43 which carries the type bar mechanism is normally in such a position that if a circuit should be closed in the middle or tens column of digits the 125 type bar 57 would print in the tens column, as the circuit does not pass through or actuate either of the shifting coils 46, 47; but if a circuit closer in the hundreds column is used, then the shifting coils 47 are energized, 130

with the result that the armature 49 is drawn over, carrying the type bar mechanism such a distance to the left as will bring the impact of the type bar in the hundreds column on the paper web of the recorder, and in like manner a circuit closer in the units column of digits will actuate the coil 46 and thus cause the type bars to print in the units column.

10 For the purpose of explaining more fully the circuits, it should be noted that the shifting coils 46, 47, are double, one of the coils L being wound low resistance and the other coil H high resistance. The circuit 15 wire 130 from the hundreds column of digits is connected up with the L magnet of coils 47, and its other terminal by a branch wire 131, with a spring finger 132 which is parallel with a spring finger 133 that is adapted 20 to be moved over by the armature, and contact with finger 132 when the magnet is excited. The other magnet H, of the coils 47, has one of its terminals connected up in common 25 with the magnet L, and its other terminal by a wire 134 with the spring finger 133 and also with the battery 135 by wire 136. The other pole of the battery has a wire 137 which leads to a common 138, and between this common and the entrance plate 30 are the coils 56 for actuating the type bars, the circuit wires from the type bar coils to the entrance plate being designated by 139.

The tens column of digits has a wire 140 which leads directly to the battery through 35 wire 136, and wire 37, connects the other terminal of the battery with the common 138 through the type printing coils and return circuit wires 139, thus actuating the type printing bars without passing through 40 either the shifting coils 46, 47, or the time printing coils 96.

The circuit from the units digits passes over the wire 143 to the low winding L of the coils 46, thence through the branch wire 45 144 to the spring finger 145. The high resistance magnet H has its terminal wire connected up with the spring finger 147, and also with the return wire 136 which goes to the battery, from which point the circuit 50 is again completed through wires 137, 138, printing coil 56, and wire 139.

We will assume that the number to be signaled at the entrance plate, or at the outlying station, is 357; the operator presses the 55 button 3 in the hundreds column thus actuating the L and H magnets 47, causing the armature 49 to be drawn over and thus moving the carriage laterally a sufficient distance to print the 3 in the hundreds column; and 60 the further action of the movement of the armature 49 is to contact the fingers 132, 133, thus cutting out the high resistance coil 8. During the initial impulse, as the high resistance coil H is in the circuit, there is not 65 enough energy to actuate the type bars 56,

but as soon as the high resistance coil is thus cut out, the circuit is sufficient to perform the printing operation. When the circuit is again opened, the springs 53 return the armature to its central or intermediate position between the poles of the magnets, so that when the digit 5 in the tens column is signaled, the type bar prints that digit without requiring any movement on the part of the carriage. The digit 7 is then signaled 70 in the units column, and the coils 46 are energized, drawing over the armature 49 and type bars so that the corresponding number is printed in the units column. Up to this time there is no other print or character on the paper web excepting the number printed which has been signaled from the employees entrance plate, but the "In" or "Out" designation from the entrance plate, or a watchman's signal mechanism is 75 thrown into position for printing on the paper web. The type printing wheels (which are actuated by a master clock, and are necessarily in an electric circuit independent of the circuits in the recorder) have 80 not, up to this time, printed the date or time on the paper web, nor has the "In" or "Out" or the watchman's designation been 85 printed, although those characters have been moved, as stated, into position ready 90 to be printed, and it is now in order that the operation of printing the date and the other 95 designations on the paper web shall take place immediately after the signal number has been printed. This is accomplished by 100 placing the time printing coils in an independent circuit from one pole of the battery 135, by a wire 150, to the time printing coils 96, thence by wire 151 to a finger 152 parallel with a spring finger 145, and so 105 related therewith that when the armature 49 is drawn over and the spring finger 147 moves the finger 145 laterally, the latter will contact with the finger 154 and thus establish a circuit through the time printing coils 110 96 and cause them to draw up the armature 86. The result is that the printing pad is moved downwardly, making the time impression on the paper web, as well as the 115 watchman's designation and the "In" and "Out" characters. As the levers 85, which carry the printing pad, return to their normal position by the action of the spring 66, the dogs 88, engaging with the ratchet wheel 86, turn the tape roller 85 so as to progress 120 the paper 94 one space. The "in" and the "out" coils 40 and 30, respectively, are connected up with their respective circuit closers by a wire 154 which goes to one side of the battery and the other side of the battery connects the common 138 by the wire 137. From the common 138 is a conductor 125 which connects with one terminal of each of the coils 30, 40, the other terminal of the coil 30 having a wire 156 which goes to the 130

"out" circuit closer in the entrance plate, and the other coil 40 has a wire 157 which goes to the "in" circuit closer.

What I claim as new, is:—

- 5 1. An electric recording instrument, comprising a frame, a time printing mechanism adapted to print the time and other suitable designations across a paper web, a set of type printing bars at each end of the frame 10 below the time printing mechanism, electrically operated, and adapted to print on a paper web in line with and at one end of the time print. 70
- 15 2. An electric recording instrument, comprising a time printing mechanism adapted to print the time and other suitable designations across a paper web, a set of type printing bars below said mechanism, electrically-operated, and means for shifting 20 said bars laterally or parallel with the line of the print of the time printing mechanism, said type bars being adapted to print on the paper web in line with and at one 75 end of the time print. 80
- 25 3. An electric recording instrument comprising a time-printing mechanism, having below said mechanism two sets of oppositely-disposed type bars electrically operated adapted to print on a paper web in line with the print of the time-printing mechanism, said type bars being mounted 30 to move laterally by electrical means. 85
- 35 4. An electric recording instrument, comprising a base having thereon a carriage which has a shifting motion laterally, said carriage having thereon a set of type printing bars, the printing types of which radiate through a common point, and electromagnets on said base and an armature on 40 the carriage coöperating with said magnets, whereby the carriage may be shifted in either direction a limited distance. 90
- 45 5. An electric recording instrument, comprising a base having centrally two pairs of magnet coils oppositely-disposed, a laterally-movable carriage on said base having an armature which projects down between the poles of the two pairs of magnets, type printing bars operatively mounted on 50 said carriage, and means for normally holding said armature midway between the poles of the magnets, said magnets operating to shift the carriage laterally in either direction. 100
- 55 6. An electric recording instrument, comprising a base having centrally two pairs of magnet coils oppositely-disposed, a laterally-movable carriage on said base having an armature fixed thereto which projects down between the poles of the two pairs of magnets, type printing bars on said carriage electrically operated and radiating to a point or common center, time printing mechanism, and a platen to receive the impact of the printing types, said magnets 60 105
- operating to shift the carriage laterally to print in either the units, tens or hundreds places on a recording tape. 110
7. An electric recording instrument, comprising a base having attached to said base a pair of electromagnets, a laterally-movable carriage on said base having an armature between the poles of said magnets, a set of type printing bars on said carriage, each operated by an electromagnet which is in circuit with the type bar magnets for shifting the carriage laterally, and a time printing mechanism having means in the same circuit for impressing the time on the paper web from the time printing wheels. 115
8. An electric recording instrument, comprising a base having thereon a laterally-movable carriage and type bar printing mechanism electrically-operated, and a removable frame having therein time printing wheels, printing ribbon and paper web rollers, and a platen to receive the impact of the type of the printing bars. 120
9. In an electric recording instrument, a frame having thereon time printing wheels, and a printing ribbon, said ribbon being mounted on wheels transversely across the paper web, and having means for automatically reversing the direction of the movement of said printing ribbon. 125
10. In an electric recording instrument, a frame having therein time printing wheels and a printing ribbon mounted on wheels, one edge of each wheel being toothed, a triangularly-shaped pawl between said toothed wheels and adapted to engage with either, said pawl being pivotally-mounted on the upper end of a laterally-swinging arm, the lower end of said arm being pivoted to a vertically-movable printing pad, a spring to normally hold the triangularly-shaped pawl and swinging arm in line, said pawl and arm having means thereon whereby the wheel having the pawl in engagement therewith will cause the arm to swing over to the opposite wheel when the ribbon on the latter wheel has been entirely unwound and causes a tension on the ribbon. 130
11. In an electric recording instrument, a removable frame having therein time printing wheels, and above the wheels a vertically-movable printing pad, and an inking ribbon, and a ribbon-reversing mechanism connected with the vertically-movable printing pad, a pair of paper web feeding rollers in the frame, and a hinged oscillating frame for carrying forward the paper web, and for moving downwardly the printing pad, and moving the printing ribbon. 135
12. An electric recording instrument, having time printing means and digit or numeral printing means operating independently of each other, and electrically connected up in different circuits, the two systems being so connected that the time printing 140

- mechanism is actuated by the numeral printing means.
13. An electric recording mechanism, having a set of type bars for printing digits, a laterally-shifting carriage on which said type bars are mounted, and a time printing mechanism connected up in circuit, the said shifting carriage, type bars and printing mechanism being operated by a single circuit closer.
14. An electric recording mechanism, having a set of type bars for printing digits, a laterally-shifting carriage on which type bars are mounted, in combination with a time printing mechanism, the said time printing mechanism being operated only after the shifting mechanism has been laterally shifted to the units side of the numeral column, and not until the type bar mechanism has been actuated.
15. An electric recording mechanism, provided with a frame having a set of type bars for printing digits, a laterally-movable carriage on which said type bars are mounted, two pairs of fixed oppositely-disposed magnets, one of high electrical resistance, and the other of low electrical resistance, an armature fixed to the laterally-movable carriage and operating between the poles of said magnets, time printing mechanism, magnets for operating said time printing mechanism, a circuit including all of said magnets, and contact mechanism operated by the movement of said carriage for controlling the connections of said magnets in said circuit.
16. An electric recording instrument, comprising time printing mechanism, magnets controlling the position of said printing mechanism, electro-magnetically operated type bars, and circuits including said magnets and electromagnets.
17. An electric recording instrument, comprising time printing mechanism, magnets controlling the position of said printing mechanism, a plurality of electro-magnetically operated type bars, circuits including said magnets and electro-magnets, means for carrying a paper strip in position to be acted upon by said printing mechanism and said type bars, and means for relatively laterally displacing said strip carrying means and said type bars.
